Patented June 8, 1920.

FIG. 1.

FIG. 2.

FIG. 3.

INVENTOR

William Louden.

UNITED STATES PATENT OFFICE.

WILLIAM LOUDEN, OF FAIRFIELD, IOWA.

DEVICE FOR BENDING METALLIC TRACK-RAILS.

1,342,554.

Specification of Letters Patent.

Patented June 8, 1920.

Application filed November 10, 1919. Serial No. 336,828.

To all whom it may concern:

Be it known that I, WILLIAM LOUDEN, a citizen of the United States, residing at Fairfield, in the county of Jefferson and 5 State of Iowa, have invented a new and useful Improvement in Devices for Bending Metallic Track-Rails, of which the following is a specification.

My invention relates to means for bending 10 metallic overhead track-rails, and it consists of a novel construction and arrangement of a pair of portable metallic plates to receive and hold the rails to be bent, and which can be taken into the building or 15 structure in which the overhead track is to be installed, and be attached to opposite sides of a stationary timber, and by inserting a section of the rail in openings in said plates, it may be bent or curved in any direction to fit the location in which it is to be 20 installed, substantially as hereinafter set forth.

In the accompanying drawings forming a 25 part of this specification, Figure 1 is a perspective embodying my invention and showing a partially bent track-rail in position to be further bent to shape. Fig. 2 is an enlarged horizontal section on line 2-2 of Fig. 1, the track-rail being removed. Fig. 3 is an 30 enlarged inside view of one of the bending plates which are duplicates of each other.

Referring to the drawings, A represents a 35 vertically disposed timber, which may be a post in a building in which an overhead track-rail is to be erected. B is a section of the track-rail being bent which is angular in cross section and C-C are the bending plates attached to opposite sides of the timber A and extended out beyond the edges of 40 one of its sides. The plates C are preferably attached to the timber A by lag screws D which are passed through holes E in the plates C.

The plates are preferably strengthened 45 and retained in relation by ribs or flanges F on their projecting ends which bear against the adjoining edges of the timber A, and serve to stay the plates and prevent them from becoming twisted on the timber as will be hereafter explained. The plates may be 50 further provided with a number of inwardly projecting points G, which will be forced into the timber and will also help to prevent the plates from being twisted thereon.

55 In the portions of one or both of the plates outside of the ribs or flanges F which pro-

ject beyond the timber A, openings H are formed to approximate the general contour of the rail to be bent, and on the edges of these openings may be thickened portions I 60 which serve to strengthen the plates and help to prevent them from cracking at the openings when under a strain. To bend the rail B all that is necessary is to insert it in the openings H of the plates C, and then pry 65 on the extended end of the rail sufficiently to cause it to bend. This may be done in any direction desired,—upward, downward, or sidewise, as may be required. Usually it is only necessary to bend the rail upward or 70 downward.

It is necessary that the track-rail be prevented from rotating in the openings H, otherwise the upward and downward bends might become inclined or sidewise bends in 75 the track-rail, and vice-versa. Also that the openings H in both of the plates be entirely surrounded by substantial material. There will be considerable strain on the plates, but being secured to opposite sides of the timber A by bolts or lag screws D, and being provided with the ribs or flanges F and thickened portions I, and, if desired, with the inwardly projecting points G, the plates will stand a strain sufficient to bend an ordinary track-rail without being broken or 80 twisted out of shape.

In the drawings the openings in both of the plates are shown to conform approximately to the cross-section contour of the 90 track-rail. This is preferable but not indispensable. All that is necessary is to have the opening in one of the plates provided with recesses, or a recess, to catch on an angular portion of the track-rail, and thus 95 prevent the rotation of the track-rail in the opening while it is being bent.

If the projecting end of the rail should be 100 too short to get a sufficient pry to bend it, a piece of pipe of sufficient size and length to get the necessary leverage may be slipped over the end of the rail, or other suitable means may be used to get sufficient lateral pressure to do the necessary bending. Usually all that is necessary is for the operator to take hold of the extended end of the rail, or the auxiliary pipe when used, and press on it sufficiently upward, downward, or sidewise to produce the necessary 105 bend. The plates C being substantially duplicates, and of the structure described, may be taken into the building, or other place 110

where the track is to be erected, and may be readily secured to a post of a size greater laterally than the attaching faces of the plates without the interference of any of the parts. By this arrangement the track-rail can be readily and quickly bent to suit the location in which it is to be mounted. If at first the rail should not be properly bent it can be quickly replaced and bent again, and again if necessary, until it will be made to fit its location without having to remove it from the building in which it is to be installed. The openings H being made to correspond with the contour of the track there is no liability of the track being improperly inserted or being rotated therein whereby it might be bent in the wrong direction, so that the wheel supporting flanges of the track-rail might become uneven, and out of proper relation to the wheels of the trolley or the carrier to run thereon. The device is exceedingly cheap and simple, and is also exceedingly expeditious and effective in operation.

25 What I claim is—

1. In a device for bending a track-rail having an angular cross-section, the combination with a pair of companion plates, comprising, attaching-portions adapted to be secured to the opposite sides or faces of a post and beyond such attaching-portions provided with extensions alining with the attaching - portions, said extensions having corresponding angular openings adapted to receive and substantially conform to the angularity of a rail-section to be bent.

2. In a device for bending a track-rail having an angular cross-section, the combination with a pair of companion plates, comprising, attaching-portions adapted to be secured to the opposite sides or faces of a post and beyond such attaching - portions provided with extensions, one of said extensions having an angular opening adapted to receive and substantially conform to the angularity of a rail-section to be bent.

3. The combination of a pair of metallic plates adapted to be secured without interference of any of the parts to the opposite sides of a timber of any substantial size with

ends extending beyond one side of the timber, flanges on the inner sides of the extended ends of the plates bearing against the adjacent edges of the timber, and openings in the extended ends of each of the plates beyond the flanges, through which a metallic track-rail may be passed and be bent in any direction by lateral pressure thereon, the openings being formed to fit the general contour of the track-rail to prevent rotation of the rail therein.

4. In a device of the character described, the combination with a pair of companion plates, comprising, flat attaching - portions adapted to be secured to the opposite sides or faces of a post rectangular in cross-section, each of said plates having on its inner face a vertically disposed flange adapted to overlap the front face of such post, and beyond such flange provided with an extension having an opening, the opening of one of such extensions being angular and approximating the angularity of the rail-section to be received and bent.

5. The combination with a pair of companion plates, comprising, flat attaching- portions adapted to be secured to the opposite sides or faces of a post rectangular in cross-section, each of said plates having on its inner face a vertically disposed flange adapted to overlap the front face of such post, and beyond such flange provided with an extension having an opening, the openings in said extensions corresponding and having an angularity agreeing substantially with that of the rail-section to be bent.

6. The combination with a pair of companion plates, comprising attaching-portions adapted to be secured to the opposite sides of a post, said plates, beyond their attaching-portions having extensions adapted to project beyond the front face of said post and each provided with an opening adapted to receive a rail-section to be bent, said openings being of such shape as will adapt them to engage one or more flanges of said rail section and prevent rotation of the rail section therein.

Fairfield, Iowa, October 28th, 1919.

WILLIAM LOUDEN.
